2 SHEETS—SHEET 2.

UNITED STATES PATENT OFFICE.

WILLIAM RICE, OF NEW YORK, N. Y.

FIREPROOF FILM-REEL.

1,339,366.

Specification of Letters Patent.

Patented May 4, 1920.

Application filed September 24, 1919. Serial No. 325,985.

To all whom it may concern:

Be it known that I, WILLIAM RICE, a citizen of the United States, and a resident of the city of New York, borough of Brooklyn, in the county of Kings and State of New York, have invented a new and Improved Fireproof Film-Reel, of which the following is a full, clear, and exact description.

10 This invention relates to a film reel, and aims to provide a device of this nature which shall be entirely fireproof, so that no possibility of an explosion occurring in the operator's booth will exist.

15 A further object of this invention is the provision of a film reel in which a film may be transported and be guarded against any accident.

20 A still further object of the invention is the construction of a reel by means of which the end of the film may readily be attached to the securing means with which it is to be associated.

25 Another object of the invention is the provision of structure incorporated in my film reel which will make it possible to have free access to the interior of the reel at any time this becomes necessary.

30 Reference is had to the accompanying drawings which illustrate one practical embodiment of my invention, and in which—

Figure 1 is a side view of my improved form of reel;

35 Fig. 2 is a sectional view taken along line 2—2 of Fig. 1;

Fig. 3 is a sectional side view taken along line 3—3 of Fig. 4;

Fig. 4 is a plan view of the same; and

40 Fig. 5 illustrates the core associated with my reel and the fastening means constructed in connection therewith.

In all these views like reference numerals 45 designate similar parts, and the reference numeral 1 indicates an annular band which is provided with inwardly-extending side flanges 2. The inner faces of the flanges 2 have associated with them guide rings 3 which are spaced therefrom and into such spaces project the outer edges of disks 4 50 forming side walls. Secured adjacent the inner edges of the disks 4 are shouldered members 5 in turn conveniently secured at their outer ends to a hub 6 keyed, as indicated by the reference numeral 7, to a shaft 8.

55 A core, including an annular band 9 pro-

vided with suitable film-end securing means 10, is mounted between the inner ends of the disks 4 and is secured in this position, serving to insure rigidity of the entire structure 60 as well as accomplishing its purpose as a core and film-end attaching means. A shouldered flange member 11 is secured to the members 5 adjacent their inner ends and serves to form, in connection with the 65 shouldered member 5, a pocket provided with an annular slot in its upper face.

Brace ribs 12 have their upper ends conveniently secured to the outer faces of the side flanges 2, the lower ends extending 70 downwardly through the slot formed in the annular pocket shoulder construction of the member 5 and the shouldered flange member 11 and may have conveniently associated with such lower ends a flat guide ring 13 75 positioned within such pocket.

An opening is formed in one of the disks 4, conveniently intermediate the core member and the band 1, so that the interior of the reel may be accessible for permitting the 80 securing of the end of the film and the film-securing means 10. Obviously, it will be impractical to have this opening uncovered during the operation of the machine, due to the fact that great danger of accidental 85 ignition of the film would exist, and with this in view, I provide a pair of guides 14 between which there may be slidably mounted a door 15 provided with a finger projection 16 and a pin 17 adjacent its upper 90 edge. A pivoted keeper 18 serves to engage the pin 17 and retain the door 15 in closed position when the same is lowered, but it will be noted that upon the door being raised it will be first necessary to move the keeper 95 18 outwardly so as to permit of this operation. It will now be understood that the disks 4 move with respect to the band 1, and by associating with one of the side flanges 2 a depending lug 19, it will be obvious that 100 the lug would strike the keeper 18, when it is moved outwardly so as to permit of the raising and lowering of the door 15, thus preventing any movement of the shaft 8 and its associated parts other than approxi- 105 mately one revolution. This, of course, would preclude any possibility of the reel being rotated as would be necessary during the operation of a moving picture projector, and would immediately give notice to the 110 operator of the projector that the door 15 was not closed, due to the fact that the reel

would fail to operate after making one revolution, due to the keeper engaging the lug 19.

A pair of guide strips 20, terminating at their upper ends adjacent an opening formed 5 in the band 1, are conveniently mounted within such opening on a pair of conventional film rollers 21 against which the film strip may bear without danger of mutilation. A similar pair of rollers 22 may be 10 provided beyond the ends of the strips 20 for the same purpose.

A second hand opening 23 is formed in the annular band 1, and with a view of closing this opening, I associate, preferably with 15 the upper half of my band 1, a guideway 24 in which there is slidably mounted a curved strip 25 normally held, by means of a spring 26, from uncovering the hand opening 23, and a further movement of the strip 25 being prevented by means of a stop and pin 27 associated with the flange 2 and strip 25 respectively.

The strip 25 is provided with an opening which, when such strip is in its normal position, alines with the opening in which the film rollers 21 are positioned. A door 28 acted upon by any suitable means, such as a spring 29, serves to normally close the same, against which action, however, the door may 30 be held back by any means, such as a clip 30.

It will be noted that I may provide in the usual manner a resiliently held, foldable stop pin 31 with the outer end of the shaft 8, which precludes any possibility of an accidental removal of the hub of such shaft; and, further, that cushions of rubber, such as 32, may be associated with the outer face of the flange 2 so that the same may frictionally engage the inner face of a casing 40 and thus insure against any rotational movement of the band.

It will now be seen in operation that a film may readily be inserted between the rollers 21 subsequent to the door 28 being 45 clipped by means of the clip 30 into its open position against action of the spring 29, and that such film may extend between the guide strips 20 and past the rollers 22. The keeper 18 may now be moved back, permitting the 50 door 15 to be raised and thus allowing the end of the film to be secured to the film-engaging means 10 of the annular band 9 comprising the core.

It will now be appreciated that the film 55 or reel may be operated by imparting power to the shaft 8, which will result in the hub 6 and its associated disks 4, together with the core housed within the same, being rotated, resulting in a normal winding action. However, should the operator forget to close the door 15, the keeper 18 will be engaged by the lug 19 and operation of the machine will be 60 impossible.

Should it now occur, as is often the case, 65 that the film breaks, the operator may cause

a cessation of the power imparted to the shaft 8, which will result in the stopping of the rotation of the disks 4; and he may now slide the strip 25 within the guides 24 against the action of the spring 26 so that 70 the lowermost edge of the same will slide beyond and uncover the hand opening 23, permitting the broken ends of the film to be joined together. The action of the spring 26 will, of course, move the strip 25 back to its 75 normal position, insuring a complete covering of the hand opening 23.

For the purpose of shifting the reels, it will now be appreciated that the film may be readily wound upon the core, and by releasing the door 28 from the clip 30 a casing 80 is provided which will hold the film in its proper position at all times and prevent any possibility of the destruction of such film by accidental ignition. Also, it will be understood that should the focus of the rays result 85 in the ignition of the film during operation, the spaced guide strips 20, as well as the film rollers 21, will render it impossible for the burning part of the film to directly reach the 90 interior of the film reel and that the film will be smothered by passing between the rollers 21, guide strips 20 and rollers 22.

Obviously, any number of modifications 95 may well be resorted to without in the least departing from the scope of the claims.

Having thus described my invention, I claim as new and desire to secure by Letters Patent:

1. A film reel including a hub, side walls 100 secured to such hub, stationary means encircling the outer edges of such side walls, one of such side walls being provided with an opening adapted to be closed by a door, and means for preventing complete rotation of such side walls with respect to such stationary means when the door is in open position.

2. A film reel including a hub, side walls 110 secured to such hub, stationary means encircling the outer edges of such side walls, one of such side walls being provided with an opening adapted to be closed by a door, means for retaining such door in closed position, and means associated with such stationary means adapted to extend into the path of travel of the door retaining element when the door is in open position.

3. A film reel including a hub, side walls 120 secured to such hub, stationary means encircling the outer edges of such side walls, one of such side walls being provided with an opening adapted to be closed by a door, a keeper adapted to engage a portion of such door, and a lug extending from such 125 stationary means, such lug projecting into the path of travel of the keeper when the door is in open position.

4. A film reel including a hub, side walls 130 for such hub, a stationary band encircling

- the outer edges of such side walls, such band being provided with an opening through which the film is to be introduced into said reel, means associated with such opening 5 for smothering any fire which may be burning that portion of the film entering the reel, such means including a pair of rollers, a pair of spaced film guide strips extending from such rollers, and a second pair of 10 rollers beyond the ends of such film guiding strips, and a door secured to such band adjacent said opening, and being capable of covering the same.
5. A film reel, including a hub, side walls 15 secured to such hub, a stationary band encircling the edges of such side walls, and brace ribs having one of their ends secured to such band and extending inwardly from a number of radial points, the inner ends of 20 such brace ribs being bent so as to extend within a slot forming a part of said hub.
6. A film reel, including a hub, side walls attached to said hub, a stationary band encircling the outer edges of such side walls, 25 and members associated with such band, such members being adapted to bear against the inner face of a casing within which said reel may be positioned.
7. A film reel, including a hub, side walls 30 attached to said hub, a stationary band encircling the outer edges of said side walls and rubber cushions associated with such band, such rubber cushions being adapted to bear against the inner face of a casing within which said reel may be positioned. 35
8. A film reel, including a hub, comprising a shaft engaging means, a shouldered member associated with said means, a shouldered flange member secured to said shouldered member and having one of its edges spaced therefrom, annular plates attached to said shouldered member, a stationary band encircling the edges of such plates, and brace ribs having one of their ends attached to said band and extending inwardly beneath said shouldered member, and shouldered flange member, and a guide ring, the inner ends of such brace ribs being attached to said ring. 40
9. A film reel, including a core, side walls 45 extending from such core, a stationary annular band encircling the outer edges of such side walls, guide rings associated with such band, a curved strip conforming to such band, and being mounted in said guide ways, stops for limiting the movement of such strip, and a spring having one of its ends secured to said band, its opposite end being attached to said strip, whereby to normally hold such strip in a position to 50 cover an opening formed in said band. 55
